PIEZOELECTRIC CRYSTAL HOLDER

John M. Wolfskill, Erie, Pa.

Application August 7, 1947, Serial No. 767,149

32 Claims. (Cl. 171—327)

1

This invention pertains to an apparatus for mounting piezoelectric quartz crystals, more particularly, it pertains to mounting thin high frequency piezoelectric crystals to facilitate handling of such crystals, and provide improved performance over the prior art holders.

It is an object of this invention to provide contiguous electrodes of varying areas to elicit good response from piezoelectric crystals on different harmonics.

It is another object of this invention to make good electrical contacts to plated electrodes of piezoelectric crystals at such a point or area as to reduce the damping action of such contact as well as the contact resistance.

It is another object of this invention to provide a rigid support not only for lateral movement of crystal blanks but also to prevent strain in the crystal blank due to its mounting or clamping supports.

Another object of this invention is to enable the crystal blank to be plated or loaded after mounting so that it may be adjusted to an exact operating frequency by deposition of additional metal over the base plated electrode without removing it from its mounting, or have its mounting affect this frequency adjustment afterwards.

Another object of this invention is to enable the handling of quartz blanks lapped to as thin as .001" so that they may be rigidly clamped and mounted into the holder without breakage during the operation.

It is another object of this invention to provide rigid mounting means of sufficiently small proportions, and of such materials that it may be readily sealed in a hermetically sealed holder, so that no deleterious effects will be had on the unit from the effects of the support means materials.

In the prior art the mounting of high frequency crystals either fundamental or harmonic type, was always associated with a large percentage of breakage in the quartz blanks. This was particularly true of crystals which used contiguous electrodes. It has been found that with these contiguous electrodes better harmonic performance is obtained, since the series capacity which is usually associated with pressure type mountings where an airgap is employed, introduced a considerable reduction in activity. It is, therefore, recognized that electrodes deposited either by evaporation, sputtering, fired, metal plated or otherwise, provides better high fre-

2

quency response with less damping on the crystal's oscillation.

Various methods have been employed in the prior art to mount such plated crystals including that of small metal clips which make contact and support the crystal, small wire loops in which the crystal edge is forced between the adjacent turns of a spring type loop, and sleeve type supports in which the crystal is slid between the open section of a small slotted tube.

All of these methods have the disadvantage of stressing the crystals beyond its elastic limits and causing fracture. These stresses may cause twisting in the quartz blank, bending at the edges, chipping, etc., resulting in a defective unit. Such stressing may not necessarily take place during the mounting operation, but subsequent to it, by a slight distortion in the external pin connection when the crystal unit is plugged into a socket; during the sealing operation, or during extreme changes in temperature over which most crystal units are required to operate satisfactorily. All of this is particularly true on crystal blanks less than .010" in thickness.

This invention overcomes all of these difficulties in a unique manner by providing, first of all, two flat surfaces between which the crystal blank is clamped on its periphery. Such peripheral clamping means may be either round, square or rectangular. The ceramic or clamping rings are first lapped on the side that contacts the crystal and then a coating of silver is fired to this flat lapped surface. Connection to this plated ring is also fired onto the ceramic on the inner circle and on the outer surface bringing the contact to the outside unlapped side of the ceramic ring. The plated crystal is then placed between these two annular supports, which are then placed between two small spring clamps which hold the entire assembly together and make contact to the plated crystal electrodes through the silver plating that has been fired onto the ceramic. Small depressions or cavities are formed on the outside of the rings to accommodate the spring clamps. This centers the entire assembly and provides a rigid support for the crystal as well as its associated ceramic rings and contact means.

If the crystal electrodes are plated over the entire area of the blank, it is desirable to have the ceramic ring silvered around the entire periphery. If, however, only a small area of the crystal is used for the crystal electrode it is only necessary to silver the lapped ceramic ring directly over the pigtail connection to the central crystal electrode. This is a particular advantage

on high frequency crystals used with high order of harmonics where it is desirable to reduce the capacity of the crystal holder and any extraneous capacity outside the activated electrode area to a minimum.

Various forms of plating can be used on the crystal electrodes themselves, either evaporated, sputtered or fired spots of gold, silver, or aluminum. It is desirable from an electrolysis standpoint and from a contact potential standpoint to provide the same metals for the plated electrodes on the crystal as is used on the ceramic rings, since these two metals contact and if they are dissimilar, contact potentials may be set up which might cause corrosion or disintegration at the point of contact of either one of the metals. Since silver or gold is easily fired to the ceramic, silver or gold electrodes on the crystal provides an excellent combination.

Once the crystal blank is mounted, the entire holder assembly may be inserted into a metal evaporating plater and the unit may then be loaded with evaporated metal to the desired frequency by having the crystal oscillate during the operation. This is a particular advantage on thin crystals because the crystal blanks need only be handled during the initial mounting operation, and the incidence of fracture due to repeated handling is greatly reduced.

Other means of holding the two annular rings may be employed such as flat leaf springs. However, it is a feature of this invention to enable the expansion of the springs by means of a simple expansion tool for the insertion of the complete assembly into the spring clips.

Another feature of the invention is the peripheral clamping of the blanks. This has a tendency to eliminate spurious responses in the crystal, and consequently small activity dips throughout a temperature range. It provides a definite electro-mechanical termination for the edge or edges of the crystal blank.

Further details of this invention will be apparent to those skilled in the art to which it relates from the following specification, claims and drawings, in which briefly

Figure 1 is a perspective view of the thin quartz crystal and mounting with the housing removed;

Figure 2 is a vertical sectional view through the quartz crystal mounting and housing taken along the line 2—2 of Figure 3;

Figure 3 is a view taken along the line 3—3 of Figure 2;

Figure 4 is a side view of one of the ceramic rings embracing the quartz crystal;

Figure 5 is a sectional view along the line 5—5 of Figure 4;

Figure 6 is another side view of the ceramic ring showing the side opposite to that shown in Figure 4;

Figure 7 is a modified form of ceramic ring;

Figure 8 is a sectional view of the ceramic ring taken along the line 8—8 of Figure 7;

Figure 9 is a sectional view taken along the line 9—9 of Figure 7;

Figure 10 is a view showing the other side of the ceramic ring from that shown in Figure 7;

Figure 10a is a view similar to Fig. 10 with only one coating 27 of silver or gold thereon;

Figure 11 is a view in fragmentary perspective of an embodiment of this invention housed in a glass tube, and

Figure 12 is a sectional view of the base of the tube shown in Fig. 11.

Referring to the drawings in detail, the thin

quartz crystal 10 is shown embraced by a pair of ceramic rings 11 that are disposed so as to clamp the circumferential portions of the crystal 10 therebetween by the spring action of the resilient wire supports 12. Each of the spring clamps 12 is provided with projections 13 fitting into small cavities formed in the ceramic rings 11 so that the assembled rings and quartz crystal are supported by the springs 12 in suitably rugged fashion to withstand handling such as the unit will receive in the course of ordinary use. The mid portions 14 of the members 12 are bent into a loop to substantially encircle the upper ends of the contact pins 15 that are supported on the base 16 of the housing by glass insulation beads 17. These mid portions 14 may be soldered or welded to the ends of the pins 15 and the glass beads 17 are also firmly joined both to the pins 15 and to the base 16. The whole crystal and mounting assembly is supported on the base 16 and enclosed in the housing 16a that fits into the groove 16b formed in the base and may be soldered therein.

The piezoelectric crystal blank 10 may be employed for frequency stabilization, and generation and absorption of high or ultra-high frequency electrical oscillations. This piezo-electric crystal blank consists of a crystal element that may have a thickness as small as $\frac{1}{1000}$ of an inch and the major faces thereof may be cut substantially parallel to the X-axis of the mother crystal and at an angle between +20 and +40° to the optic axis. An angle of 30 or 35° with respect to the optic axis has been found satisfactory. However, other types of piezoelectric crystal cuts may be employed and these cuts may be either parallel to or at an angle with respect to the X-axis or the optic axis. Furthermore, the crystal may be made of slightly convex contour and the surfaces of the major faces of the crystal blank should be free from even minute depressions.

Suitable electrodes 18 and 19 are provided to each major face of the quartz crystal 10 by processes such as plating, sputtering, evaporation in vacuum and the like. The lead of electrode 18 is connected by a solder or silver connection 20a to a suitable metallic coating 20 extending around one of the ceramic rings 11 in contact with the projection 13 formed on one of the spring clamps 12 as shown in Figures 1, 2 and 3 and the other electrode 19 is connected to a similar metallic coating 21 on the other ceramic ring 11 contacting a projection 13 on the other spring clamp 12. As a result the contact pins 15 are connected, one to the quartz crystal electrode 18 through the metallic coating 20 on a portion of one of the ceramic rings 11 and the other electrode 19 is connected to the other pin 15 through the metallic coating 21 on a portion of the other ceramic ring 11. The electrodes 18 and 19 are each preferably of an area that is small compared to the area of each of the major faces of the crystal blank 10. For example in a crystal blank having a diameter about $\frac{1}{2}$ inch the diameter of the electrode may be about $\frac{1}{4}$ inch. Furthermore, the electrodes 18 and 19 may be of the same diameters or they may be of different diameters and the crystal blank may be of circular or rectangular shape or any other convenient shape. The electrodes may likewise be of circular, rectangular or other convenient shapes. Each of the electrodes 18 and 19 are provided with a "pig-tail" connection, the "pig-tail" connection of the electrode 18 being connected through the globule 20a of solder or silver to the coating 20 and one of the pins 12, and the electrode 19 being connected to a suitable

"pig-tail" connection to the coating 21, this coating 21 being connected also through a globule of solder or silver to the "pig-tail" associated with the electrode 19.

Details of construction of the ceramic rings 11 are shown in Figures 4 to 10 inclusive, Figures 7 to 10 inclusive showing a modified form. In Figure 4 is shown a side view of a ring 11 such as shown in Figure 1 and this ring may be made of various insulation materials such as synthetic porcelain, fused quartz, glass, as well as synthetic resins. The rings 11 instead of being made of the materials set forth above may be cut from quartz crystal material the same as the piezoelectric crystal blank and in this case these rings may be cut from blanks that are cut at substantially the same angle or angles at which the piezoelectric crystal blank is cut so as to have a linear coefficient of expansion the same as the piezoelectric crystal blank and thereby prevent any slippage between the rings 11 and the piezoelectric crystal blank 10 through temperature cycling referred to as hysteresis effect. Hysteresis effect may be explained as follows. If the frequency of the piezoelectric crystal blank is measured at room temperature and the temperature of the crystal blank is then raised or lowered and then brought back to the initial temperature and the frequency measured after this temperature cycle, it is frequently found that the second frequency is no longer exactly the same as the initial frequency and that the initial frequency can be restored by jarring the piezoelectric crystal blank or by taking it through a temperature cycle in the opposite direction.

One side of this ring 11 is provided with a metallic coating 20 extending at least partially around the ring so as to contact one of the electrodes 18 for example and this coating also extends into the cavity 22 receiving the projection 13 of the spring clamp 12 that is employed for supporting the crystal assembly and connecting one of the crystal electrodes to one of the pins 15. The other side of the insulation ring 11 is provided with a cavity 23 for receiving one of the projections 13 of the other spring clamp 12. However, no metallic coating surrounds this cavity inasmuch as no connection is to be made to the spring clamp 12 from this side of this insulation ring. The surface of the ring 11 next to the quartz crystal 10 is provided with a metallic coating 24 that consists of silver fired to the surface of the ring and this silvered surface engages the opposite surface of each of the rings 11 may be used to cement these rings directly to the opposite surfaces of the crystal blank 10 and for this purpose cements of various types including a low temperature fired silver bonding cement such as now on the market may be employed. Both of the rings 11 are made in this manner and each of these rings is provided with a metallic coating such as coating 22, the coating of one ring making contact with one of the supporting clamps 12 and the coating on the other ring making contact with the other supporting spring clamp 12. In Figures 8, 9 and 10 is illustrated a ring 25 similar to the ring 11 except that the ring 25 does not engage the quartz crystal throughout its circumference inasmuch as the ring 25 has two cut-away portions 26. As a result only the silvered surfaces 27 engage the corresponding surfaces of the quartz crystal. These silvered surfaces 27 may be employed to cement the ring 25 to the opposite surfaces of the crystal blank 10 and furthermore,

if desired, only one of the projecting areas of the ring 25 need be provided with a coating 21 as shown in Fig. 10a. These rings 25 are particularly adapted for use with high frequency crystals employing high order harmonics where it is desirable to reduce the capacity of the crystal holder. The rings 25 are also provided with cavities 22 and 23 for receiving ends 13 of the spring clamps and one of these cavities of each ring 25 is also provided with a metallic coating for the purpose of connecting the associated spring clamp 12 to an electrode of the quartz crystal.

In Figs. 11 and 12 is illustrated an embodiment of this invention in which the piezoelectric crystal blank and associated members are positioned in a glass housing 28 which may be similar to glass housings provided to vacuum tubes. This glass housing is provided with a base 29 sealed to the contact pins 15 that project out of the base and are adapted to be used for connecting the piezoelectric crystal blank 10 to an electric circuit. These pins 15 are sealed to the glass base 29 in air-tight fashion and for this purpose various glass to metal seals may be employed. The base 29 is sealed to the housing 28 around the circumference of the base and this operation is accomplished by suitable glass working technique. The interior of the glass housing 28 may be evacuated if desired so that the piezoelectric crystal blank 10 may be operated substantially in a vacuum or an atmosphere of inert gas such as neon, nitrogen, helium and the like, may be provided inside of the housing.

While I have described this invention in detail with respect to a preferred embodiment, it is of course apparent that modifications therein may be made without departing from the spirit and scope of this invention and therefore I do not desire to limit this invention to the exact details shown and described except as defined by the following claims.

What is claimed is:

1. A piezoelectric crystal apparatus assembly for extremely thin piezoelectric crystal blanks comprising a piezoelectric crystal blank having a thickness between 0.01 inch and 0.001 inch, means for reinforcing said crystal blank without substantially impairing the operation thereof and means for connecting said crystal blank to an electrical circuit.
2. A piezoelectric crystal apparatus assembly for extremely thin piezoelectric crystal blanks comprising a piezoelectric crystal blank having a thickness between 0.01 inch and 0.001 inch, means cemented to said crystal blank for reinforcing said crystal blank without substantially impairing the operation thereof and means for connecting said crystal blank to an electrical circuit.
3. A piezoelectric crystal apparatus assembly for extremely thin piezoelectric crystal blanks comprising a substantially circular piezoelectric crystal blank having a thickness between 0.01 inch and 0.001 inch, ring-shaped means for reinforcing said crystal blank without substantially impairing the operation thereof and means for connecting said crystal blank to an electrical circuit.
4. A piezoelectric crystal apparatus assembly for extremely thin piezoelectric crystal blanks comprising a piezoelectric crystal blank having a thickness between 0.01 inch and 0.001 inch, means for clamping said crystal blank for reinforcing said crystal blank without substantially impairing the operation thereof and means for

connecting said crystal blank to an electrical circuit.

5. A piezoelectric crystal apparatus assembly for extremely thin piezoelectric crystal blanks comprising a piezoelectric crystal blank having a thickness between 0.01 inch and 0.001 inch, means engaging peripheral portions of said crystal blank for reinforcing said crystal blank without substantially impairing the operation thereof and means for connecting said crystal blank to an electrical circuit.

6. A piezoelectric crystal apparatus assembly for extremely thin piezoelectric crystal blanks comprising a piezoelectric crystal blank having a thickness between 0.01 inch and 0.001 inch, ring-shaped elements engaging peripheral portions of said crystal blank for reinforcing said crystal blank without substantially impairing the operation thereof and means for connecting said crystal blank to an electrical circuit.

7. A piezoelectric crystal apparatus assembly for extremely thin piezoelectric crystal blanks as set forth in claim 1 wherein the means for reinforcing the crystal blank comprises ceramic elements engaging only the peripheral portions of said crystal blank major faces, the surfaces of said ceramic elements engaging said major faces being lapped.

8. Piezoelectric crystal apparatus comprising a thin piezoelectric crystal having a thickness between 0.01 inch and 0.001 inch, a pair of ceramic rings, each of said rings having one surface thereof lapped to a high degree of flatness, means for cementing the lapped surfaces of each of said rings to peripheral portions of the major faces of said crystal blank for reinforcing said crystal blank, said ceramic rings each having small holes in substantially diametrically opposed portions thereof, and spring means positioned in said small holes for supporting said crystal blank and said rings in assembled relation.

9. Piezoelectric crystal apparatus comprising a thin piezoelectric crystal of circular configuration having a thickness between 0.01 inch and 0.001 inch, a pair of ceramic rings, each of said rings having one surface thereof lapped to a high degree of flatness, means for cementing the lapped surfaces of each of said rings to peripheral portions of the major faces of said crystal blank for reinforcing said crystal blank, said ceramic rings each having small holes in substantially diametrically opposed portions thereof, and spring means positioned in said small holes for supporting said crystal blank and said rings in assembled relation.

10. Piezoelectric crystal apparatus comprising a thin piezoelectric crystal having a thickness between 0.01 inch and 0.001 inch, a pair of ceramic rings, each of said rings having one surface thereof lapped to a high degree of flatness, means for cementing the lapped surfaces of each of said rings to peripheral portions of the major faces of said crystal blank for reinforcing said crystal blank, said ceramic rings each having small holes in substantially diametrically opposed portions thereof, resilient wire elements having the ends thereof lodged in said small holes, and means attached to said wire elements for supporting said crystal blank and said rings in assembled relation.

11. Piezoelectric crystal apparatus comprising a thin piezoelectric crystal, a pair of ceramic rings, each of said rings having one surface thereof lapped to a high degree of flatness, means for cementing the lapped surfaces of each of said rings

to peripheral portions of the major faces of said crystal blank for reinforcing said crystal blank, said ceramic rings each having small holes in substantially diametrically opposed portions thereof, and spring means positioned in said small holes for supporting said crystal blank and said rings in assembled relations.

12. Piezoelectric crystal apparatus comprising a thin piezoelectric crystal, a pair of ceramic rings, each of said rings having one surface thereof lapped to a high degree of flatness, means for cementing the lapped surfaces of each of said rings to peripheral portions of the major faces of said crystal blank for reinforcing said crystal blank, and means for supporting said crystal blank and said rings in assembled relations.

13. Piezoelectric crystal apparatus comprising a thin piezoelectric crystal, a pair of ceramic rings, each of said rings having one surface thereof lapped to a high degree of flatness, means for cementing the lapped surfaces of each of said rings to peripheral portions of the major faces of said crystal blank for reinforcing said crystal blank, said ceramic rings each having small holes in substantially diametrically opposed portions thereof, resilient wire elements having the ends thereof positioned in said small holes, and means attached to said wire elements for supporting said crystal blank and said rings in assembled relations.

14. A piezoelectric crystal apparatus assembly for extremely thin piezoelectric crystal blanks comprising a piezoelectric crystal blank having a thickness between 0.01 inch and 0.001 inch, a pair of electrodes for said crystal blank contiguous to the central portions of the major faces of said crystal blank, an element having substantially greater mechanical strength than said piezoelectric crystal blank cemented to peripheral portions of one of said major faces of said crystal blank for strengthening said crystal blank and connections to said electrodes for connecting said crystal blank to a desired circuit.

15. A piezoelectric crystal apparatus assembly for extremely thin piezoelectric crystal blanks comprising a piezoelectric crystal blank having a thickness between 0.01 inches and 0.001 inches, a pair of electrodes for said crystal blank contiguous to the central portions of the major faces of said crystal blank, elements having substantially greater mechanical strength than said piezoelectric crystal blank engaging peripheral portions of said major faces of said crystal blank for strengthening said crystal blank and having said crystal blank therebetween, resilient members for engaging said elements and pressing said elements against said crystal blank and connections between said resilient members and selected ones of said electrodes for connecting said crystal blank to a desired circuit.

16. A piezoelectric crystal apparatus assembly for extremely thin piezoelectric crystal blanks comprising a piezoelectric crystal blank having a thickness between 0.01 inch and 0.001 inch, a pair of electrodes for said crystal blank contiguous to the central portions of the major faces of said crystal blank, ring-shaped elements having substantially greater mechanical strength than said piezoelectric crystal blank, said ring-shaped elements being cemented one on each side of said crystal blank for engaging peripheral portions of said major faces of said crystal blank for strengthening said crystal blank and holding said crystal blank therebetween, resilient members for engaging said elements and pressing said

elements against said crystal blank and connections between said resilient members and selected ones of said electrodes for connecting said crystal blank to a desired circuit.

17. A piezoelectric crystal apparatus assembly for extremely thin piezoelectric crystal blanks comprising a piezoelectric crystal blank having a thickness between 0.01 inch and 0.001 inch, a pair of electrodes for said crystal blank contiguous to the central portions of the major faces of said crystal blank, elements having substantially greater mechanical strength than said piezoelectric crystal blank cemented to peripheral portions of said major faces of said crystal blank for strengthening said crystal blank and holding said crystal blank therebetween, resilient members for engaging said elements and pressing said elements against said crystal blank and connections between said resilient members and selected ones of said electrodes for connecting said crystal blank to a desired circuit.

18. A piezoelectric crystal apparatus assembly for extremely thin piezoelectric crystal blanks comprising a piezoelectric crystal blank having a thickness between 0.01 inch and 0.001 inch, a pair of electrodes for said crystal blank contiguous to the central portions of the major faces of said crystal blank, ring-shaped elements having substantially greater mechanical strength than said piezoelectric crystal blank engaging peripheral portions of said major faces of said crystal blank for strengthening said crystal blank and holding said crystal blank therebetween, resilient members for engaging said elements and pressing said elements against said crystal blank and connections between said resilient members and selected ones of said electrodes for connecting said crystal blank to a desired circuit.

19. A piezoelectric crystal apparatus assembly for extremely thin piezoelectric crystal blanks comprising a piezoelectric crystal blank having a thickness between 0.01 inch and 0.001 inch, means having substantially the same coefficient of expansion as said crystal blank for reinforcing said crystal blank without substantially impairing the operation thereof and means for connecting said crystal blank to an electrical circuit.

20. A piezoelectric crystal apparatus assembly for extremely thin piezoelectric crystal blanks comprising a piezoelectric crystal blank having a thickness between 0.01 inch and 0.001 inch, means having substantially the same coefficient of expansion as said crystal blank cemented to said crystal blank for reinforcing said crystal blank without substantially impairing the operation thereof and means for connecting said crystal blank to an electrical circuit.

21. A piezoelectric crystal apparatus assembly for extremely thin piezoelectric crystal blanks comprising a substantially circular piezoelectric crystal blank having a thickness between 0.01 inch and 0.001 inch, ring-shaped means having substantially the same coefficient of expansion as said crystal blank for reinforcing said crystal blank without substantially impairing the operation thereof and means for connecting said crystal blank to an electrical circuit.

22. A piezoelectric crystal apparatus assembly for extremely thin piezoelectric crystal blanks comprising a piezoelectric crystal blank having a thickness between 0.01 inch and 0.001 inch, ring-shaped insulation means having substantially the same coefficient of expansion as said crystal blank for reinforcing said crystal blank without substantially impairing the operation thereof and

means for connecting said crystal blank to an electrical circuit.

23. A piezoelectric crystal apparatus assembly for extremely thin piezoelectric crystal blanks comprising a piezoelectric crystal blank having a thickness between 0.01 inch and 0.001 inch, means having substantially the same coefficient of expansion as said crystal blank engaging peripheral portions of said crystal blank for reinforcing said crystal blank without substantially impairing the operation thereof and means for connecting said crystal blank to an electrical circuit.

24. A piezoelectric crystal apparatus assembly for extremely thin piezoelectric crystal blanks comprising a piezoelectric crystal blank having a low temperature coefficient of expansion and having a thickness between 0.01 inch and 0.001 inch, said crystal blank being cut at an angle between 20 and 40 degrees with respect to the crystalline optic axis, means having substantially the same coefficient of expansion as said crystal blank for reinforcing said crystal blank without substantially impairing the operation thereof and means for connecting said crystal blank to an electrical circuit.

25. A piezoelectric crystal apparatus assembly for extremely thin piezoelectric crystal blanks comprising a piezoelectric crystal blank having a low temperature coefficient of expansion and having a thickness between 0.01 inch and 0.001 inch, said crystal blank being cut at an angle substantially 35° with respect to the crystalline optic axis, means having substantially the same coefficient of expansion as said crystal blank for reinforcing said crystal blank without substantially impairing the operation thereof and means for connecting said crystal blank to an electrical circuit.

26. Piezoelectric crystal apparatus comprising a thin piezoelectric crystal blank having a thickness between 0.01 inch and 0.001 inch, a pair of quartz rings, each of said rings having one surface thereof lapped to a high degree of flatness, means for cementing the lapped surfaces of each of said rings to peripheral portions of the major faces of said crystal blank for reinforcing said crystal blank, and means for supporting said crystal blank and said rings in assembled relation.

27. Piezoelectric crystal apparatus comprising a thin piezoelectric crystal blank of circular configuration having a thickness between 0.01 inch and 0.001 inch, a pair of quartz rings, each of said rings having one surface thereof lapped to a high degree of flatness, means for cementing the lapped surfaces of each of said rings to peripheral portions of the major faces of said crystal blank for reinforcing said crystal blank, said quartz rings each having small holes in substantially diametrically opposed portions thereof, and spring means positioned in said small holes for supporting said crystal blank and said rings in assembled relation.

28. Piezoelectric crystal apparatus comprising a thin piezoelectric crystal blank having a thickness between 0.01 inch and 0.001 inch, a pair of quartz rings, each of said rings having one surface thereof lapped to a high degree of flatness, means for cementing the lapped surfaces of each of said rings to peripheral portions of the major faces of said crystal blank for reinforcing said crystal blank, said quartz rings each having small holes in substantially diametrically opposed portions thereof, resilient wire elements having the

ends thereof lodged in said small holes, and means attached to the said wire elements for supporting said crystal blank and said rings in assembled relation.

29. Piezoelectric crystal apparatus comprising a thin piezoelectric crystal blank, a pair of rings having substantially the same coefficient of expansion as said crystal blank, each of said rings having one surface thereof lapped to a high degree of flatness, means for cementing the lapped surfaces of each of said rings to peripheral portions of the major faces of said crystal blank for reinforcing said crystal blank, said quartz rings each having small holes in substantially diametrically opposed portions thereof, and spring means positioned in said small holes for supporting said crystal blank and said rings in assembled relation.

30. Piezoelectric crystal apparatus comprising a thin piezoelectric crystal blank, a pair of rings having substantially the same coefficient of expansion as said crystal blank, each of said rings having one surface thereof lapped to a high degree of flatness, means for cementing the lapped surfaces of each of said rings to peripheral portions of the major faces of said crystal blank for reinforcing said crystal blank, and means for supporting said crystal blank and said rings in assembled relation.

31. Piezoelectric crystal apparatus comprising a thin piezoelectric crystal blank having a thickness between 0.01 inch and 0.001 inch, a pair of quartz rings, each of said rings having one surface thereof lapped to a high degree of flatness, means for cementing the lapped surfaces of each

of said rings to peripheral portions of the major faces of said crystal blank for reinforcing said crystal blank, said quartz rings each having small holes in substantially diametrically opposed portions thereof, and spring means positioned in said small holes for supporting said crystal blank and said rings in assembled relation.

32. A piezoelectric crystal mounting for extremely thin piezoelectric crystal blanks comprising a piezoelectric crystal blank having a low temperature coefficient of expansion and having a thickness between 0.01 inch and 0.001 inch, said crystal blank being cut at an angle of +30° with respect to the crystalline optic axis, means having substantially the same coefficient of expansion as said crystal blank for reinforcing said crystal blank without substantially impairing the operation thereof and means for connecting said crystal blank to an electrical circuit.
